(57) **CLAIM**

The ornamental design for display equipment with roller, as shown and described.

DESCRIPTION

FIG. 1 is a top perspective view of the display equipment with roller, showing my new design;

FIG. 2 is top plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a bottom plan view thereof; and,

FIG. 8 is a bottom perspective view thereof.

The broken lines illustrate environmental structure of the display equipment with roller, which forms no part of the claimed design.
